TYPESETTING MEANS IN RECORD CONTROLLED PRINTING MACHINES

James Last, London, England, assignor to International Business Machines Corporation, New York, N. Y., a corporation of New York

Application September 19, 1947, Serial No. 774,902
In Great Britain September 19, 1946

11 Claims. (Cl. 101—93)

1

This invention relates to a print unit adapted to be used in accounting and the like machinery.

An object of this invention is to provide an improved print unit adapted for use in an accounting machine, the unit operating in response to timed impulses for printing any one of a full range of characters or symbols while maintaining the full speed of the machine.

Another object is to provide a printing mechanism in which the inertia and kinetic energy of its parts are minimized so as to prevent destructive wear at high speeds.

Still another object is to provide an improved mechanism for printing characters in close proximity to each other.

Yet another object is to provide a printing mechanism in which the blurring is minimized when a number of carbon copies are printed.

These desiderata involve the simplification of the mechanism for operating the type bearing member since a space equal only to the character width is available for the operating mechanism. The characters being made solid with the type bearing member lightens this member, but the number of characters sets the size of this moving part. The ability to deal with the carbon copies necessitates high speed hammer blows, together with high speed rebound.

In accordance with the present invention, therefore, the print unit has individual type bearing members, the members being movable for the purposes of selecting a type. A positive coupling means is provided for each of the type bearing members, and a positive driving means common to all members is engageable selectively by each of the coupling means to initiate said selecting movement. There is also provided means for disengaging all of the coupling means from the driving means at a fixed instant in the cycle to terminate said movement, and means individual to each member is actuated by a timed impulse for effecting engagement of said coupling means with the driving means.

In the preferred form of the print unit, any one of the full number of characters possible with a given arrangement of timed impulses may be selected. It is preferred to employ an annular type bearing member which is positively driven to the approximate selected position, and then centered while free from the locating drive. A printing from a type element is effected by a light hammer acting through a metal strip, the paper and a carbon ribbon on the type face, the hammer being made to rebound under the action of a spring which threw it forward. The type

2

bearing member is positively restored to its home position, and means are provided for stopping this member in its home position with but little shock.

It is an important feature of this invention that only one setting mechanism is provided and that this may be repeatedly operated under the control of successive impulses in one cycle.

One consequence of this is that all the single impulse selections result in characters being selected, whereas when second impulses are used only for the purpose of modifying a first impulse selection, four characters become available.

In the embodiment shown, the impulses are electrical and are received by a group of magnets, one to each column. They might equally well, however, have been obtained from mechanical movements and delivered to members of the same nature as the magnet armatures illustrated.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a section of a print unit, taken transversely of the print wheel axis.

Fig. 2 is a view of the left-hand end of the unit showing diagrammatically, the main gear trains and the main clutch but having the main cam unit removed.

Fig. 3 is a part front view showing part of the main cam unit, the magnet box and portions of the set lever assembly being removed.

Fig. 4 is a plan view with a middle portion omitted.

Fig. 5 is a separate front elevational view of the main cam unit.

Fig. 6 is a separate right-hand side view of the main cam unit.

Fig. 7 is a view of part of the print unit as seen from the upper side of Fig. 4 and showing the sheet feed control.

Fig. 8 is a part section of the magnet box and set plungers taken on the plane 8—8 of Fig. 1.

In the embodiment illustrated, each of a plurality of print wheels 1 bears fifty characters which are selected by timed electrical impulses derived from the electrical sensing of a card of the well known Hollerith type. As these cards have only 12 index points in each column, the numbers 0 to 11 are selected by single impulses and the remainder by two impulses variously

timed according to a code. It is a convention to refer to the 12 index points, in order of sensing, as 9 to 0, X, Y. The two hole combinations used in the code are 9 to X with Y, 9 to 0 with X, 9 to 1 with 0, 9 to 2 with 1, the total number of different selections being 12 (single hole) + 11 + 10 + 9 + 8 = 50, as stated above.

The type wheel 1, illustrated, has 53 gear tooth spaces 2 separated by lands 69 and is angularly positioned by the rotation of the set gear 3, the teeth 4 of which engage with the spaces.

Fifty of the lands between the spaces bear characters and three are blank. In its initial unset position, one of the blank lands 69 is at the printing line. The sequence of characters and blanks is as follows, two dots at half height indicating a blank:

0.....	--	18.....	3.....	36.....	(
1.....		19.....	T.....	37.....	6
2.....	E	20.....	C.....	38.....	7
3.....	O	21.....	4.....	39.....	X
4.....		22.....	L.....	40.....	G
5.....	11	23.....	4.....	41.....	)
6.....	/	24.....	U.....	42.....	B
7.....	10	25.....	D.....	43.....	8
8.....	1	26.....	-.....	44.....	Y
9.....		27.....	M.....	45.....	H
10.....	A	28.....	5.....	46.....	%
11.....	14	29.....	V.....	47.....	Q
12.....	J	30.....	E.....	48.....	9
13.....	2	31.....	*	49.....	Z
14.....	S	32.....	N.....	50.....	I
15.....	B	33.....	6.....	51.....	&
16.....	14	34.....	W.....	52.....	R
17.....	K	35.....	F.....		

It will be seen that between each pair of digits are four other characters, the double digits 10 and 11 being treated as special characters. Many other arrangements are possible to suit particular cases.

Where two impulses are employed to make a selection, the function of the second impulse is to modify the position of the type wheel which would be arrived at were the first impulse used alone. Thus, impulses at 1, Y, O, or X times, respectively, when they are second impulses produce modifications of position to the extent of $\frac{1}{5}$, $\frac{2}{5}$, $\frac{3}{5}$ or $\frac{4}{5}$ of the pitch between successive digit positions.

Now referring to Fig. 1, there is one magnet 5 to each print wheel 1. The arrangement of the magnets in plan is shown in Fig. 4 where it will be seen that they are in two rows in staggered relation. An impulse received by a magnet is synchronized with the arrival of the corner 6 of a groove 7 in the set cam 8, at the tooth 9 of the set lever 10. The set cam 8 controls the operating mechanisms for all of the print wheels 1, and the operating mechanism for each of the print wheels includes a separate lever 10. The impulse withdraws the toe 11 of the armature 12 from interference with the plunger 13 which is engaged with the lever 14 interlocked with the set lever 10. The set cam 8 makes one rotation per operating cycle in the direction shown by the arrow 65 and the timing of the impulse determines which groove 7 will be adjacent to the tooth 9 when it occurs. The set lever 10 is copivoted with the actuator 15, and the actuator latch 16 pivoted on the actuator is retained engaged with the shoulder 17 on the set lever 10 by the spring 18. This spring causes the tooth 9 to enter the selected groove 7 and also to lower the rear end 19 of the actuator, so that the set latch 20 pivoted on the clutch pawl 21 can engage the upper side of the end 19 by the action of the spring 22 and bell crank 23.

The continued rotation of the set cam 8 discharges the tooth 9 from the groove 7 depressing the set lever 10 and through the latch 16 rais-

ing the end 19 of the actuator 15 together with the set latch 20. This disengages the clutch pawl 21 from the ring of the clutch 24. At the same time the depression of the set lever 10 lowers the lever 14 and the plunger 13 allowing the toe 11 of the armature 12 to reengage the upper end of the plunger 13 and so preventing further action of the set lever until another impulse is received by the magnet 5. This magnet is the subject of my copending United States application Ser. No. 717,050, now Patent No. 2,493,885, patented January 10, 1950.

In the embodiment being described, the clutch 24 is of the type which is the subject of my copending United States application Ser. No. 614,486 and consists of a wheel member and a ring member. A spring tends to advance the ring member with respect to the wheel member through one tooth pitch. The clutch shown has 20 teeth and these are shortened by ten circular scallops which are formed in both clutch and ring members. When the clutch pawl 21 engages the ring and the check pawl 25 engages the wheel member, so as to retain the ring member retarded with respect to the wheel member, the scallops in both members coincide.

The drive gear 26 common to all columns runs continuously in the direction indicated by the arrow 27 at ten times the speed of the set cam 8. This ratio depends upon the number of zones employed in the setting code and is, in fact, twice the number of zones. Thus, a four zone code having three characters between successive digits requires the drive gear 26, when of 20 teeth as in the present case, to run at eight times the speed of the set cam 8.

In the condition now referred to, the drive gear 26 closely fits a scallop in the clutch but without touching it.

40 The disengagement of the clutch pawl, as described, allows the clutch spring to rotate the ring member so that its scallop first bears on the top of a tooth of the drive gear 26 and then enters the following tooth space. The ring tooth continues to engage the following drive gear tooth, until the limit of its movement with respect to the wheel member is reached when it begins to rotate the wheel, the composite gear thus constituted by the clutch then being completely engaged with the drive gear 26.

45 The wheel member engages a coupler train, one to each column, comprising the wheels 28 and 29. The wheels 28 and 29 together with the clutches 24 are carried in a coupler frame 30 which is pivoted about the axis of the clutches 24. This arrangement allows the smaller gear 31, which is integral with the gear 29, to be engaged with or disengaged from the set gear 3. Engagement is effected in a manner to be described later, 50 just before the leading corner 6 of the earliest groove 7 in the set cam 8 reaches the tooth 9 of a set lever 10 and is maintained until after the latest impulse time.

55 The discharge of the tooth 9 from a set cam groove 7, therefore, initiates the rotation of the set gear 3 and its related print wheel 1.

The set latch 20 is retained lifted by its shoulder 32 which the spring 22 causes to engage the frame 33. In this position the upper 60 arm 34 of the set latch 20 has its lip 35 in the path of a lip 36, 37, 38 or 39 on the knock-off cam 40 which rotates continuously in the direction of the arrow 41 at equal speed with the set cam 8.

65 Supposing a single impulse only to have been received, the rotation of the print wheel will

continue being positively driven through the clutch until the lip 36 on the knock-off cam 40 by engaging the lip 35 of the set latch 20 depresses the arm 34 and so disengages the latch 20 from the frame 33. This allows the spring 22 to re-engage the clutch pawl 21 with the ring member of the clutch 24 and to arrest it with its scallop concentric with the drive gear 26. The rotation of the wheel member of the clutch 24 continues, restraining the clutch spring until the scallops of wheel and ring again coincide, the check pawl 25 preventing reverse movement of the wheel due to the clutch spring. In this condition the clutch is disengaged and the type wheel 1 is positioned in accordance with the timing of the impulse received by the magnet 5. It should be said that the lip 42 on the check pawl 25 engages the underside of the clutch pawl 21 just as the clutch pawl is about to release the ring, so that the completion of the clutch pawl movement outwards from the clutch 24 disengages the check pawl 25 from the clutch wheel to avoid trailing during the type wheel setting operation.

The lips 36, 37, 38 and 39 of the knock-off cam 40 are related, respectively, to 1, nought, X and Y positions in a card column.

Similarly, the last four grooves 7 in the set cam 8 are related, respectively, to the 1, nought, X and Y positions.

It will be seen that the nought, X and Y grooves are of different widths. They all, however, have their leading corners 6 at the uniform pitch common to all the grooves. The fact is that, while the index points on the card pass at uniform intervals of time and the consequent releases of the set lever 10 to enter a groove are similarly timed, the ensuing disengagement of the clutch pawl 21 is timed by the passage of the following wall of the groove 7. Thus, the impulse is registered when it occurs but its effect may be delayed for some portion of an index point interval. This is done to differing extents in the case of the nought, X and Y impulses by giving different widths to their grooves 7 in the set cam 8. The following wall of each of these grooves is related to its particular lip of the knock-off cam 40. Thus, the starting of the type wheel train by the nought groove is terminated by the lip 37 of the knock-off cam 40, after the type wheel has moved $\frac{1}{2}$ of a digit pitch. The movement started by the X groove is terminated by the lip 38 after the type wheel has moved $\frac{1}{3}$ of a digit pitch, and the movement started by the Y groove is terminated by the lip 39 after $\frac{1}{4}$ of a digit pitch has been passed.

These movements, due to nought, X or Y impulses, take place independently of whether a previous impulse has been given, for the reason that the nought groove does not disengage the clutch pawl 21 until the lip 36 of the knock-off cam 40 has terminated a movement due to an earlier impulse.

This is also true of an impulse from the index point 1, provided it has not been preceded by an earlier impulse. When, however, the "1" impulse occurs as a second impulse, the tooth 9 of the set lever 10 enters the "1" groove in the set cam 8 while the clutch pawl 21 is still disengaged. This means that the link 43 pivoted to the lower clutch pawl arm is in its forward position and its foot 44 supports the tail 45 of the trailer 46 against rearward movement. At the time of the "1" impulse, the lip 47 of the delay cam 48 is passing the land 49 on the trailer 46, thereby preventing its forward movement so that the 75

pivot of the trailer 46 on the actuator latch 16 is prevented from moving forward when the tooth 9 of the set lever 10 enters the "1" groove. This causes the actuator latch 16 to be disengaged from the set lever 10, the immediately subsequent depression of which by the set cam 8 then failing to raise the rear end 19 of the actuator 15. The continued rotation of the delay cam 48 in the direction of the arrow 50 results in the lip 47 engaging the end 51 of the leg 52 of the actuator 15 and by displacing it to the rear, raising the end 19 at the same time reengaging the actuator latch 16 with the set lever 10. The position of the end 51 is such that this movement of the actuator occurs after the clutch pawl 21 has arrested the clutch 24, due to the action of the zero lip 36 on the knock-off cam 40, releasing the set latch 20. Thus, the set latch 20 is again lifted and the clutch 24 reengaged. This reengagement, due initially to a "1" impulse following an earlier impulse, occurs towards the end of the period in which a nought setting would be made, and the resulting movement of the type wheel is of the extent of $\frac{1}{2}$ of a digit pitch, the lip 37 of the knock-off cam 40, which is responsible for terminating a nought setting, also serving to terminate this shorter setting due to a "1" impulse following an earlier impulse.

The disengagement of the actuator latch 16 in 30 the manner just described is avoided, when the "1" impulse is not preceded by an earlier impulse, for then the impulse occurs when the link 43 has not been advanced, the clutch 24 being still held disengaged by the clutch pawl 21. Therefore, although the delay cam 48 engages the land 49 on the trailer 46, the tail 45 of the latter is unsupported by the foot 44 of the link 43. The trailer 46 then swings idly when the tooth 9 on the set lever 10 enters the groove in the set cam 8, and the actuator 15 behaves as though integral 40 with the set lever 10 as in the case of earlier impulses, or the nought, X, or Y impulses.

After the point in the operating cycle at which a setting due to a Y impulse will have been completed, the coupler wheels 31 are swung about the axis of the clutches 24 out of engagement with the set gears 3, and the aligner bail 53 is lowered, the springs 54 then causing the noses 55 of the aligners 56 to enter the adjacent gear spaces 2 50 in the type wheels 1 and rectify any small errors of alignment due to the gear train.

Attention is now drawn to the restoring shaft 57 about which the set gears 3 are pivoted. Each set gear 3 bears a projection 58, which is in the 55 path of a restoring arm 59, one to each gear 3, and keyed to the shaft 57. Just in advance of the earliest and, therefore, the greatest setting movement, the shaft 57 is rotated in the setting direction indicated by the arrow 60 to bring its 60 arms 59 to their furthest position shown chain-dotted at 61 (Fig. 1). This movement is performed at such a speed as will ensure the arms 59, always keeping ahead of the projections 58 on the gears 3 in their setting movement.

Immediately, the hammers 71 in the hammer unit 70 are released to cause printing on the sheet 80, the hammers being withdrawn at once after impact.

The bail 53 is now raised to disengage the 70 aligners 56 from the type wheels 1, and the shaft 57 is rotated to bring its arms back to the position 59 (Fig. 1). In this position, the projections 58 have been engaged by the arms 59, wherever they may have been positioned by setting movements, and brought to rest against the teeth of

the stop comb 62, thus restoring all type wheels to their initial positions with blank lands 69 at the printing line.

In a high speed mechanism such as is represented by the present embodiment, the restoring of members such as the type wheels 1 and set gears 3 and the arrest of the restoring movement against a stop member, such as the comb 62, may give rise to destructive forces seriously limiting the effective life of the parts.

For this reason, the comb 62 is not a fixed member but is pivoted about an axis 68 and has rocking movement about this axis during the restoring movement of the shaft 57. This rocking movement is such that the comb advances its teeth in a similar direction to the setting movement of the projections 58, but is retiring to its initial position at such a speed by the time the fastest moving projection 58 reaches it that no significant shock is sustained by the moving parts. The final arrest of the comb and wheels thereafter takes place after a finite negative acceleration positively controlled by which destruction of the parts by high impulsive loading, due to the sudden arrest of their masses, is avoided.

The type wheels 1 are of annular form and are individually pivoted upon and spaced by the disks 130, each of which is flanged to engage one side of its related type wheel. The disks 130 are centered upon the fixed shaft 131 and are themselves spaced by the fixed combs 132 which rest upon the shaft and pass through slots 133 in the disks. The disks are prevented from rotation by the key 134. A felt strip 135 serves to convey lubricant.

The hammer unit 70 (Figs. 1, 2) is designed to deliver a rapid blow to the back of the paper followed by a prompt rebound to avoid blurring of carbon printing. There is a hammer 71 for each type wheel 1, and each hammer has a small lever 72 pivoted to its rear end and bearing on an end face 73 of the hammer. This lever 72 has the spring 67 hooked to it. The hammers are withdrawn and their springs stretched by a lobe 74 of the rotary cam 75, which has three lobes and makes one-third of a rotation in each operating cycle in the direction of the arrow 66. The lobe 74 bears on the shoulder 76 of each hammer, and its rotation is timed so that the lobe escapes the shoulders 76 at the instant when printing is required. The forward movement of the hammers under the pull of their springs 67 engages the levers 72 with the edge of a plate 77 shortly before the hammer heads 78 deliver their blow to the back of the sheet 80 through the steel strip 79. The plate 77 furnishes a fulcrum which results in a reversing impulse being applied to each hammer and causes rebound immediately after impact, the lever 72 first pivoting on the plate 77 thereby swinging relatively away from the face 73 of the hammer and stretching the spring again. The relaxing of the spring after impact withdraws the hammer until the lever 72 again rests against the face 73. The plate 77 is adjustable edgewise of itself or in the direction of the hammer travel, to provide adjustment of the rebound distance as well as of the force of impact.

This adjustment is obtained by sliding the plate 77 diagonally on the guides 189 (Fig. 4) and is effected through the graduated lever 190 on the shaft 191 pivoted on the end plate 118 and having keyed to it the cam 192 which engages the roller 193 on a stud fixed in the plate 77. The steel strip 79 is used to distribute the blow and to pre-

vent images of the hammer heads being produced on the sheet.

The hammer unit is supported directly from the underframe by the standards 185, 186 (Fig. 2).

The front standard 186 is pivoted on the underframe at 187. The rear standard 185 is toggle-jointed and, when the lever 188 is pushed to the rear, the entire unit is withdrawn from the printing line to allow free access for the insertion of multiple sheets and for other purposes, such as the mounting of a new ribbon.

The cam 75 (Figs. 1 and 2) has keyed to it a ratchet wheel 110 (Fig. 2) having 6 teeth. The drive pawl 111 is pivoted to the arm 102 which rocks freely about the axis of the cam 75. This arm is coupled by the link 103 to the rocker 104 which is pivoted on the underframe 108 and is driven through the link 105 and crank pin 106 in the gear 107, this gear making two rotations in each operating cycle. Thus, the ratchet wheel 110 is advanced two teeth in each cycle, giving the necessary one-third rotation to the cam 75. The check pawl 109 serves to prevent reverse rotation of the cam 75.

At the opposite end of the cam 75 (Figs. 4 and 7) is keyed the three-lobed cam 112 which coacts with the V-shaped lever 113 pivoted on the stud 196 in the end plate 118, the rollers 114 bearing on the cam 112. The lever 113 has an arm 115 which is linked to the arm 116 freely pivoted about the fixed stud 117 in the auxiliary plate 195. This stud also has freely pivoted on it the gear 120 which has keyed to it the ratchet wheel 121. The gear 120 engages with the gears 122, 123 which are respectively keyed to the feed rolls 81, 82. The arm 116 has a pawl 124 which can engage the ratchet wheel 121, when permitted to do so by the mask 125, the pawl 124 being wide enough to engage both the ratchet wheel and the rim of the mask. The mask 125 is angularly adjustable by the lever 126 which contains a spring-loaded plunger 127 bearing on the notched sector 128 formed on the auxiliary plate 195. Thus, the angular adjustment of the mask determines the point in the swing of the arm 116 at which the pawl 124 will pass from the contour 129 of the mask 125 and engage the ratchet wheel 121. The arrangement is proportioned so that a feed of one ratchet tooth pitch corresponds to an advance of the sheet 80 through the conventional single line spacing.

The sheet 80 is held by the feed rolls 81, 82 in conjunction with the pressure rolls 83, 84 (see Fig. 1). The pressure rolls 83, 84 are in short lengths, each length being trunnioned at its ends in a pair of brackets 85, 86. These brackets are pivoted on the bars 87, 88 and are bridged in pairs by the plates 89, 90, at the center of each of which a spring 91, 92 is attached. The plates 89, 90 are stepped at their ends and rest freely in the slots 93, 94, in the brackets 85, 86, thus dividing the spring load equally between the two ends of each pressure roll 83, 84. A tooth 95, 96 on each bracket is freely accommodated in a V groove in each release shaft 97, 98, when the rolls 83, 84 are bearing on the sheet 80. Partial rotation of either release shaft 97, 98 by the levers 99, 100 will relieve the pressure of its associated pressure rolls 83 or 84.

In a print unit such as the present, in which the characters are to be printed closely adjacent in a line, the support of the inking ribbon must be derived from its control at the ends of the line, intermediate guides being of little value. The

method of feeding the ribbon is, therefore, involved and will now be described.

The inking ribbon 250 (Figs. 1, 2, 4 and 7) is wound upon two spools 251, 252, which are mounted upon spindles 253, 254 journaled in the brackets 255, 256. A common rock shaft 257 (also in Fig. 1) actuated by the arm 258, link 259 and pin 260 extending from the rocker 104 serves to drive either spool as required, the rocker giving two strokes in each cycle as explained earlier with reference to the hammer unit. A common link 262 couples the drive reversing arrangements. Taking the spool 251, the spindle 253 has keyed to it a flange 263 bearing a pin 265 for driving the spool. Beneath the bracket 255 is a ratchet wheel 267 also keyed to the spindle 253. Freely pivoted on a downward extension of the spindle is a mask lever 269, a reversing plate 303, and finally a drive lever 271, the fork 273 of which engages the conical stud 275 in the arm 278 which is keyed to the rock shaft 257, this connection being duplicated by the drive lever 272, and arm 277 also keyed to the other end of the rock shaft 257. Thus, the two drive levers 271, 272 are reciprocated at the same time.

Each drive lever 271, 272 bears two pawls 279, 280, 281, 282. The pawl 279 is directed so as to engage the ratchet wheel 267 and the pawl 281 similarly with respect to the ratchet wheel 268. Both levers are shown at the beginning of their feed stroke, which is of an extent sufficient to feed the ratchet wheel through two tooth pitches, although it is not called upon to do so. The engagement of the drive pawls with their ratchet wheels is controlled by the reversing plates 303, 304. These plates are connected to each other rotationally by the reversing levers 283, 284, each engaging with a notch in its related reversing plate and being pivoted on the bracket 255 or 256. These levers are coupled at their front ends by the link 262. In the figures the pawl 279 is shown resting on its reversing plate 303, which has its notch 285 in such a position that the full stroke of the lever 271 will cause the ratchet wheel 267 to be rotated through one tooth pitch.

On the opposite side of the plate 303 the check pawl 281 pivoted to the bracket 255 prevents the ratchet wheel 267 from reverse movement. The reversing plate 303 has a second notch 289 which accommodates the nose of the check pawl 281 and allows it to engage with the ratchet wheel 267. The drive pawl 281 is resting on the reversing plate 304 which is in such an angular position as to prevent the pawl 281 from engaging with its ratchet wheel 268 throughout the whole of the stroke of the lever 272 to which the pawl is pivoted. Also, the plate 304 has its check pawl notch 290 displaced from the check pawl 288 which is thus held disengaged from the ratchet wheel 268. The spool 252 is, therefore, rotated by the ribbon while this is being wound upon the spool 251.

While the ribbon is being unwound from the spool 252, the tension lever 292 has its forward end resting in the deep notch 294 in the reversing plate 304. In this position the roller 296 on the rear end of the lever 292 presses the ribbon on to the fixed guide 298, thus maintaining tension on the ribbon between the guide 298 and the spool 251. The other tension lever 291 has its forward end resting in the shallow notch 299 in the reversing plate 303, serving as a detent to retain the reversing plate system in its position. In this position the roller 295 on the lever 291

is held off the ribbon as it passes over the fixed guide 297.

The continued unwinding of the ribbon from the spool 252 eventually causes the fork 274 on the mask lever 272 to be engaged by the usual eyelet or stud, adjacent to the ends of the ribbon, and to be pulled towards the guide 298, thus rotating the mask lever 270. This mask lever has a nose 302 which has hitherto been in the position shown, such that the reversing pawl 281 could not engage it. The rotation of the mask lever now advances the nose 302 until the pawl 281 can clear the nose and at the same time engage a notch 306 in the reversing plate 304. This is done at the end of the drive stroke of the lever 272, which is still made with the pawl 281 held out of engagement with the ratchet wheel 268.

The return stroke of the lever 272 now causes the reversing pawl 281 to rotate the mask lever 270 and the reversing plate 304 until the forward end of the lever 292 rests in the shallow notch 300 in the plate 304, the lever 284, link 262 and lever 283 causing the rotation of the reversing plate 303 to such a position that the drive pawl 279 and check pawl 281 are held out of engagement with the ratchet wheel 267, and the tension lever 291 brings its roller 295 to bear upon the ribbon as it passes over the fixed guide 297.

The form of the reversing plate 304 is such that on the next driving stroke of the lever 272, the reversing pawl 281 in withdrawing from the notch 306 is displaced radially far enough to clear the nose 302 of the mask lever 270 and allow the spring 308 to restore the lever 270 to its former position. The two terminal mechanisms of the ribbon drive have now completely interchanged their functions and the interchange has been positively effected.

The foregoing explanation covers the essential functions of the unit. The provision for the relative timing of the movements will now be dealt with.

The main drive to the unit is delivered to the main gear 150 (Fig. 2) by the gear 151 pivoted on the underframe 108. The gear 150 is freely pivoted on the stud 155 fixed in the side frame 105 and is integral with the boss 152, which has a notch 153. A clutch gear 154 of the same dimensions as 150 is also freely pivoted on the stud 155 and has pivoted on it a clutch pawl 156 of hook form and adapted to engage the notch 153, when actuated by the spring 157. The gear 154 also drives the gear 107 from which the hammer and feed roll drives are taken. The tail 158 of the pawl 156 may be engaged by the arm 159, which is pivoted on the fixed stud 160 in the side frame 105. In this condition, continued rotation of the gear 154 causes the hook of the pawl 156 to be disengaged from the notch 153 and its tail 158 to arrest further rotation of the gear 154 by engaging the block 161, which is integral with the gear.

A second block 162 on the gear 154 is engaged by the hook pawl 163 also pivoted on the stud 160 to prevent reverse movement of the gear 154 when the pawl 156 is held disengaged as described. The arm 159 is forked and its other member 164 has its rounded end in the path of the block 165 on the main gear 150. This chamfered block serves to re-engage the arm 159 with the tail 158 of the pawl 156, but the angular relations are such that the block 165 escapes from the arm 164 in time for the arm 159 to be removed from the

path of the tail 158 before engaging it, should the arm 159 not be retained in its disengaging position. The spring 166 effects this withdrawal when the link 184 coupling the part 167 of the arm 159 to the plunger 168 through the two-armed rocker 169 is allowed to rise by the displacement of the armature 170 of the magnet 171 in the magnet box 172. By this means the continued operation of the print unit is dependent upon the repeated actuation of the magnet 171, 10 the cessation of which causes the clutch gear and associated mechanisms to come to rest in an unvarying position.

The auxiliary lever 173 pivoted on the part 167 enables the spring 166 to apply resilient loading to the hook pawl 163 as well as to the part 167 with the arms 159 and 164.

The timing of the various functions is performed by the cam unit 200 (Figs. 5 and 6) which is supported upon the studs 235, 155 in the side-plate 105 (Fig. 2), which enter the holes 198, 199 (Figs. 5 and 6). This unit has one cam shaft 201 and two rocker shafts 202, 203. The cam shaft 201 is driven through the adjustable coupling 204 from the gear 251 (Fig. 2) which is driven by the clutch gear 154 and makes one rotation in each operating cycle. The cams are in pairs, one of each pair being complementary to the other in form. There are five pairs of cams and the two cams of each pair are separated by a distance piece which enables each rocker to enter the space between its two related cams, the two rollers on each rocker being on opposite sides of it. The left hand pair of cams 205, 206 controls the movement of the restoring shaft 57 (Figs. 1 and 2) through the sector rocker 207, the pinion 208, the shaft 209, and the angularly adjustable coupling 210 by which the shaft 209 is direct coupled to the shaft 57, the sector rocker 207 being freely pivoted on the shaft 203.

The cams 211, 212 control the rocker 213, which is keyed to the shaft 203. This shaft provides a drive which may be used for an auxiliary purpose not related to the print unit proper and will not be referred to further. The cams 214, 215 control the rocker 216 keyed to the shaft 202. This shaft bears at its end the adjustable arm 217 which engages the shaft 218 (Fig. 1) upon which the coupler gears 29 are pivoted. The shafts 218, 219 and 220 are incorporated in the coupler frame 30 and the three shafts are keyed to the frame 30, the lowest shaft 220 upon which are the clutches 24 being trunnioned in the side frames 105, 106. Thus, the rocking of the arm 217 (Figs. 5 and 6) effects the engagement and disengagement of the coupler gears 31 with the set gears 3 (Fig. 1) by rocking the coupler frame 30 about the axis of the shaft 220. The cams 221, 222 control the rocker 223, which is freely pivoted on the shaft 202 and is linked to the auxiliary rock shaft 224 by the link 225. This shaft 224 is coupled by the adjustable coupling 226 to the stop comb 62 (Figs. 1 and 2), the purpose of which has already been described. The cams 227, 228 control the rocker 229 also freely pivoted on the shaft 202. This rocker has a stud 230 which protrudes through a clearance hole 231 in the frame of the cam unit, and this stud is coupled by the link 232 (Fig. 3) to the end of the aligner bail 53, thus effecting its positive control by the cams 227, 228.

The magnet box 172 (Figs. 1, 2, 4 and 8) has inside it the fixing bars 174 by which the magnets 5 are secured in place, their cores 175 being also registered in the combs 176. The contact jaws 75

177, 178 engage the contact pieces 179, 180 on the magnets, the lower set 177 being wired together and connected to source, each of the others 178 being individually wired to the plug sockets 181 in the end board 182, from which connections may be made to the selective circuits, one of which will control the engagement of the main clutch through the magnet 171 (Fig. 2). The paper envelopes 183 afford protection to the windings while the magnets are being handled.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A mechanism operable cyclically for printing characters in response to the sensing of holes at index points 9 to 0, X and Y in a column of 25 a card comprising, in combination, a type bearing member, means supporting said member for movement so as to locate its type in printed positions, driving connections for said type bearing member, a continuously rotating driving means, said driving connections including coupling means adapted to be coupled to said driving means, means engageable successively with said index points in the order listed for sensing holes in said card, means operating in response to the sensing of a hole at any one of said index points for effecting engagement of said coupling means to initiate movement of said member, means operating at a fixed time after the 1 index point is sensed for disengaging said coupling if it has been previously engaged by the sensing of a hole at not more than one point, and means for disengaging said coupling after different time intervals if it is engaged due to the sensing of a hole at the 0, X or Y points.

45 2. The mechanism of claim 1 including means for making said means operating to disengage said coupling at a fixed time inoperative when a hole is sensed at the No. 1 point after sensing a hole at some previous point and effecting disengagement of said coupling at a later time.

50 3. The mechanism of claim 1 in which said means for effecting engagement of said coupling in response to the sensing of a hole comprises a rotating cam having notches adapted to receive 55 a control element, said notches corresponding to said index points and each having a leading edge reaching a position to permit entry of said element in synchronism with the sensing of the corresponding index point, means for effecting movement of said element into a notch upon the sensing of a hole at the corresponding index point, said element being forced out of the notch by the trailing edge of the latter, and means actuated by said element when the latter is forced out of a notch for engaging said coupling means with said driving means.

4. The mechanism of claim 1 in which said means for effecting engagement of said coupling in response to the sensing of a hole comprises a rotating cam having notches adapted to receive a control element, said notches corresponding to said index points and each having a leading edge reaching a position to permit entry of said element in synchronism with the sensing of the corresponding index point, the width of said

notches corresponding to index points 9 to 1 inclusive being equal while the width of said notches corresponding to index points 0, X and Y are different from each other and from the other notches, means for effecting movement of said element into a notch upon the sensing of a hole at the corresponding index point, said element being forced out of a notch by the trailing edge of the latter, and means actuated by said element when the latter is forced out of a notch for engaging said coupling means with said driving means.

5. The mechanism of claim 1 including means for connecting said driving connections in driving relation with said member just before the sensing of said No. 9 index point and releasing said driving connections from said member after the sensing of the Y index point, means for centering and holding said member in its set position after said driving connections are released, means for taking a print from said member while it is held by said last-mentioned means, and means for returning said member to its unset positions after operation of said print taking means.

6. A mechanism operable cyclically for printing characters in response to the sensing of holes at index points 9 to 0, X and Y in a column of a card comprising, in combination, a type bearing member supported for movement to selected printing positions, driving connections for said member, a continuously rotating driving means, said driving connections including coupling means adapted to be coupled to said driving means, means engageable successively with said index points in the order listed for sensing holes in said card, means for connecting said driving connections in driving relation with said member during the sensing of said index points and disconnecting said driving connections after the last point has been sensed, means operating in response to the sensing of a hole at any one of said index points for effecting engagement of said coupling means to initiate movement of said member, the operation of said last-mentioned means taking place at fixed intervals after the sensing of holes at the 9 to 1 index points and taking place after different intervals on the sensing of holes at the 0, X and Y points, means operating at a fixed time after the 1 index point is sensed for disengaging said coupling if it has been previously engaged by the sensing of a hole at not more than one point, means for disengaging said coupling after different time intervals if it is engaged due to the sensing of a hole at the 0, X or Y points, means for centering and holding said member in its set position after said driving connections have been disconnected, means for taking a print from said member while it is being held, and means for returning said member to its unset position after a print has been taken.

7. The mechanism of claim 6 in which the means for effecting engagement of said coupling in response to the sensing of holes comprises a

rotating cam having spaced notches adapted to receive a control element, said notches corresponding to said index points and each reaching a position to receive said element in synchronism with the sensing of the corresponding point, means for effecting movement of said element into a notch upon the sensing of a hole at the corresponding index point, said element being forced out of the notch by the trailing edge of the latter, means actuated by said element when it is forced out of a notch for engaging said coupling, and means engageable at predetermined times with said last means if it is actuated by said element for effecting a release of said coupling.

8. The mechanism of claim 6 in which said last-mentioned means comprises a movable abutment for said member, means for moving said abutment at a decreasing speed in the direction in which said member is moved toward its unset position, said member engaging said abutment while its speed is being decreased so that said member is returned to its unset position without shock.

25 9. The mechanism of claim 6 in which said member carries digit printing type separated by type for printing different characters, and in which said means operating to engage and disengage said coupling means after the sensing of a hole at any one of said points effects a setting of said member to print a digit, while a sensing at a hole at the 9 to 1 points in combination with the sensing of a hole at one of the 1, 0, X and Y points effects a setting of said member to print one of said different characters.

30 10. The mechanism of claim 6 in which said means for taking a print comprising a hammer, a metal tape, and means for actuating said hammer for striking said tape so as to force a paper against the type on said member.

40 11. The mechanism of claim 6 in which said means for taking a print comprises a hammer, and means including a spring for actuating said hammer to force a paper against the type on said member, said spring then operating to cause rebound of said hammer.

JAMES LAST.
